FOLDING SUPPORT STRUCTURE

Harold Howe, Rowayton, Conn.

Application December 19, 1942, Serial No. 469,556

2 Claims. (Cl. 311—88)

This invention relates to a structure, such, for example, as a table, or bench, comprising a supporting surface and folding support means therefor.

Folding structures such as tables, benches and the like ordinarily have the disadvantages that even when provided with locking means their locks do not always engage when the table legs are fully opened and are therefore easily displaced from fully open position, thus rendering the structure liable to collapse, and also the legs are apt to fall out when in folded position, as the table is moved about.

An object of the invention is to overcome the aforesaid disadvantages and drawbacks of such folding structures and to provide a simple, strong, dependable, and durable folding structure. Another object is to provide such a structure which may be readily moved about in folded condition, and the support means of which may be quickly and completely opened and closed. Another object is to provide a folding structure in which the folding support means will be positively locked in open position, and held under pressure, but not positively locked, in folded position. Another object is to provide means for rigidly bracing said folding support means in unfolded position and means for exerting force coacting with said brace means to resist the initiation of folding action.

The invention accordingly consists in the features of construction, combination of elements, arrangements of parts, and in the several steps and relation and order of each of said steps to one or more of the others thereof, all as will be pointed out in the following description, and the scope of the application of which will be indicated in the following claims.

The invention will best be understood if the following description is read in connection with the accompanying drawings in which

Figure 1 is a side elevational view of a table embodying my invention;

Figure 2 is a plan view of the under surface of the table shown in Figure 1 with the legs thereof in fully folded position;

Figure 3 is a perspective view, partly broken away, of a preferred embodiment of the invention, showing in solid lines the support means in fully unfolded position, and showing in broken lines the position of the parts when in partly folded or unfolded position; and

Figure 4 is a detail view on an enlarged scale looking toward the inner side of one of the leg and brace assemblies in unfolded position;

Figure 5 is a view similar to Figure 3 showing a slightly modified form of the invention.

The term "table" as used herein in the specification and claims includes any structure comprising a surface, for receiving or supporting objects, and folding support means therefor.

The term "top," or "table top," as used herein in the specification and claims includes any surface, for receiving or holding objects, comprised in a "table" as defined in the preceding paragraph.

The table top 10 is shown herein provided with a folding support assembly comprising the legs 11 and 12 hinged to the under surface of the table top by the hinges 13 and 14 respectively, and preferably joined together by the cross member 15, and the folding brace members 16a, 16b, and 17a, 17b, joined between the table top 10 and the legs 11 and 12 respectively. The outer end of the brace member 16a is pivotally joined by pivot 18 to a block b depending from the table top 10, and the outer end of brace member 16b is pivotally joined to leg 11 by pivot 19. The inner ends of brace members 16a and 16b are pivotally joined together by pivot 20, which is positioned slightly out of alignment with the pivots 18 and 19 and slightly above a plane common to pivots 18 and 19. The brace members, 16a and 17a, are provided with stop means to prevent the members of each pair of braces from folding inwardly toward the leg hinge more than to a very limited, predetermined distance which may be desirable as hereinafter explained, while permitting folding of the brace members outwardly. In the embodiment of the invention illustrated herein in Figures 1-4, the stop means is the enlarged head h, provided at the outer end of each member 16a and 17a, adapted to abut against the cross member 15 when the brace members have reached a predetermined position.

When leg 11, for example, is in open position, and the brace members 16a and 16b are fully unfolded, any folding pressure on the leg will tend to fold its brace members inwardly thus pressing the head h of the brace member 16a against the cross member 15 and thereby preventing the folding of the brace members either inwardly or outwardly, so long as the brace members remain in fully opened position, and giving increased rigidity to the table.

Similarly the brace members 17a and 17b are pivotally joined to the table top 10 and the leg 12 respectively by pivots 20 and 21, and their inner ends are pivotally joined together by pivot

22 which is positioned slightly out of line with the pivots 20 and 21, and above a plane joining the pivots 20 and 21, and their action is the same as that of brace members 16a and 16b.

The brace means for the legs 11 and 12 are preferably interconnected by a cross bar 23. As illustrated in Figures 1-4, bar 23 extends between the brace members 16a and 17a for the respective legs, but it will be understood that bar 23 may be interposed between other like parts of the support assembly, as for example, between the brace members 16b and 17b, or between the pivots 20 and 22. Extending over the bar 23 is the free end 25 of a spring member 26, the other end of which is secured to the under surface of the table top by any suitable means. As illustrated herein the edge of the inner end of spring member 26 is recessed at 27, and a bridging channel member 28, provided with a lateral projection 29 to fit in said recess 27, extends across the inner end of the spring member and is secured to the table top, or, as illustrated herein, to the block 30, interposed between the spring member 26 and the table top and fixed to the latter, as by screws 31, thus firmly securing the spring member to the table top.

Preferably, the bar 23 is formed with a re-entrant portion or trough shaped slideway 24 in which the free end 25 of spring member 26 may be slideably seated.

It will be seen that at all times the free end 25 of spring member 26 will exert a yielding force upon the folding support assembly, transmitted in the embodiment of the invention illustrated herein, through the bar 23, both when the support means are folded and unfolded, thereby maintaining said support means in fully folded or fully unfolded position, and making it necessary to exert a positive force to initiate the unfolding or folding of said support assembly.

In the embodiment of the invention illustrated herein, when the legs 11 and 12, and therefore also the brace members 16a and 16b, and 17a and 17b, are fully unfolded, the spring means 26 disclosed herein, or equivalent means, will exert a force on the toggle arms comprising said brace members pressing the stops h against their cooperating stop means which, as illustrated herein, in Figures 1-4, is the cross member 15, thereby preventing inward folding of the brace means, and holding the brace members of each brace means with their intermediate pivot beyond a plane joining their pivotal connections to the table top and leg respectively, thus positively locking said brace members in fully extended position. The spring means thus cooperates and coacts with the brace means not only to resist folding of the table legs, but also to resist movement of said brace members into a position where it is possible for the folding action to be initiated.

When the structure is fully open, folding force exerted on the legs 11 and 12 will have no effect. Folding action of the support assembly of legs and braces can be initiated only after the brace members have been moved slightly, either by exerting a downward pull on either brace member 16a or brace member 16b, or on cross bar 23, sufficient to overcome spring member 26 and to bring the three pivots of the brace members into alignment, and to move them through aligned position until the intermediate pivot is slightly beyond and below alignment with the outer end pivots of the brace members.

When the brace members are unlocked in the manner described and the folding action is thus

initiated, the support assembly will snap from unfolded into partly folded position in a positive manner and thereafter during the folding operation the force of spring member 26 will be exerted in aiding the folding operation, and in retaining the support assembly in fully folded position, thus avoiding looseness and rattling of the legs and braces when the structure is collapsed and eliminating the need for straps or other means to hold the legs and braces in fully folded position.

In the slightly modified embodiment of the invention shown in Figure 5 the cross rod 40 is substituted for the cross bar 23, and the laterally projecting flange f on brace members 16a and 17a is substituted for the enlarged head h. The remainder of the elements of Figure 5 are as shown in the preceding figures.

The application of the spring force as illustrated herein employs the brace members 16a and 17a as lever arms causing a relatively small spring force to exert a relatively large locking force. The position of bar 23, or the depth of re-entrant portion or trough shaped slideway 24, and therefore the distance of the contact between cross bar 23 and the free end of spring member from the under surface of the table top, is preferably determined in relation to the length of the spring member and its resiliency, and may be proportioned to avoid excessive strain on the spring member, the locking force of which, as stated above, may be greatly magnified by its transmittal through the brace members 16a and 17a acting as lever arms.

The table support locking means disclosed herein may be readily applied to a plurality of folding support assemblies. Where it is applied to a table having two support assemblies each comprising two legs, one pair may be spaced further apart than another pair as illustrated in Figure 2 so that the legs of both pair may lie in the same plane when folded although the ends of one pair overlap the legs of another pair. Otherwise the elements of each folding support means may be the same and I have used like numerals with prime marks to identify like parts of the second of the two folding support assemblies indicated in Figures 2 and 3. The spring means employed for a plurality of oppositely positioned pairs of legs may conveniently be a unitary spring strip, which may be secured to the table top intermediate its free ends as shown in Figure 2.

What I claim is:

1. A table structure comprising, a top, a cross member extending transversely of the top and hingedly connected to the under surface of the table top, a plurality of supporting legs secured at their upper ends respectively to said cross member, brace means interconnected between said supporting legs individually and the table top, said brace means each comprising two members one of which is pivotally connected to one of said supporting leg members, and the other of which is pivotally connected to the table top, said members being pivotally connected together, and the member which is pivotally connected to the table top having an abutment adapted to abut against the said cross member when the table is in fully opened position, an interconnecting link extending between the brace members of said brace means respectively which are connected to the table top, and a flexible spring-like member secured at one end to the table top intermediate its ends and overlying and yieldingly pressing against said interconnecting link means whereby a force is exerted against said link means tending

to maintain said brace means respectively in fully opened position.

2. A table structure comprising a top, a pair of legs hingedly connected to the under surface of said top, brace means, individual to each of the legs of said pair of legs, interconnected between said legs respectively and the table top, the said brace means for each leg each comprising two members one of which is pivotally connected to one of said supporting leg members, and the other of which is pivotally connected to the table top, said members being pivotally connected together

5 and having means preventing said members from folding in a direction toward the table top, and an interconnecting link extending between like brace members of the brace means for each of said legs, and resilient means supported from the table top adapted to exert a yielding pressure upon said interconnecting link whereby a force is exerted against said link means tending to maintain the brace means for each of said legs in fully opened position.

10
